[57] CLAIM

The ornamental design for a wristwatch, substantially
as shown and described.

DESCRIPTION

FIG. 1 is a front elevation of a wristwatch showing my
new design;

FIG. 2 is a rear elevation thereof;

FIG. 3 is an elevation from one end thereof;

FIG. 4 is an elevation from the other end thereof;

FIG. 5 is a right side elevation thereof;

FIG. 6 is a left side elevation thereof; and

FIG. 7 is a front perspective view thereof.

The digital display is illustrated in FIG. 1 in a non-ener-
gized condition and is illustrated in an energized condi-
tion in FIG. 7 for exemplary purpose.

FIG. 3

FIG. 1
